LENS FOR LIGHTING FIXTURES

Kurt Franck, Newark, Ohio, assignor to Holophane Company, Inc., New York, N.Y., a corporation of Delaware

Filed Feb. 26, 1957, Ser. No. 45,000

Term of patent 14 years

(Cl. D48—16)

FIG. 1 is a perspective view of a lens for lighting fixtures embodying my new design;

FIG. 2 is a bottom view of a lens for lighting fixtures as illustrated in FIG. 1;

FIG. 3 is a side view of a lens for lighting fixtures as illustrated in FIG. 1;

FIG. 4 is a front view of a lens for lighting fixtures as illustrated in FIG. 1; and

FIG. 5 is a fragmentary vertical section taken on the line 5—5 of FIG. 2 and indicating the prism configuration on the exterior of the lens.

I claim:

The ornamental design for a lens for lighting fixtures, as shown.
